(57) **CLAIM**

The ornamental design for a boot protector, as shown and described.

DESCRIPTION

FIG. 1 is a right side view of my new design for a boot protector;

FIG. 2 is a left side view thereof;

FIG. 3 is a top view thereof;

FIG. 4 is a bottom view thereof;

FIG. 5 is a front view thereof;

FIG. 6 is a rear view thereof;

FIG. 7 is a plan view of my new design for the boot protector of FIG. 1 resting on a flat surface;

FIG. 8 is the opposite plan view of FIG. 7 with the end strap and the center strap being removed;

FIG. 9 is a side view thereof;

FIG. 10 is a plan view the end strap of FIG. 7;

FIG. 11 is a side view of FIG. 10;

FIG. 12 is a bottom view of FIG. 10;

FIG. 13 is a plan view the central strap of FIG. 7;

FIG. 14 is a side view of FIG. 13; and,

FIG. 15 is a bottom view of FIG. 13.

The broken line showing of the boot in the FIGS. 1-7 is for illustrative purposes only and forms no part of the claimed design.
